DESIGN FOR A LISTENER'S HEADSET

Gustav F. Braun, Elizabeth, and Frederick M. Porter, Montclair, N. J., assignors to Thomas A. Edison, Incorporated, West Orange, N. J., a corporation of New Jersey

Application November 1, 1946, Serial No. 134,462

Term of patent 14 years

(Cl. D26—14)

To all whom it may concern:

Be it known that we, Gustav F. Braun, a citizen of the United States and a resident of the city of Elizabeth, in the county of Union and State of New Jersey, and Frederick M. Porter, a citizen of the United States and a resident of the town of Montclair, in the county of Essex and State of New Jersey, have invented a new, original, and ornamental Design for a Listener's Headset, of which the following is a specification, reference being had to the accompanying drawing, forming a part thereof.

In the drawing:

Figure 1 is a front elevational view of a listener's headset showing our new design;

Figure 2 is a righthand elevational view of our headset as shown in Figure 1;

Figure 3 is an elevational view showing the in-

ner side of one receiving unit of our headset; and

Figure 4 is a bottom plan view of one receiving unit of our headset.

We claim:

The ornamental design for a listener's headset, substantially as shown.

GUSTAV F. BRAUN.
FREDERICK M. PORTER.
